US0D1100163S

(12) **United States Design Patent** (10) **Patent No.:** **US D1,100,163 S**
(45) **Date of Patent:** **** Oct. 28, 2025**

(54) **HUMIDIFYING AIR CLEANER**

(71) Applicant: **Iris Ohyama Inc.**, Sendai (JP)

(72) Inventors: **Masayuki Miyawaki**, Kakuda (JP);
Yuna Miyamoto, Kakuda (JP)

(73) Assignee: **Iris Ohyama Inc.**, Sendai (JP)

(**) Term: **15 Years**

(21) Appl. No.: **29/918,914**

(22) Filed: **Nov. 30, 2023**

(30) **Foreign Application Priority Data**

May 31, 2023 (JP) ..... 2023-011017 D

(51) **LOC (15) Cl.** **23-04**

(57) **CLAIM**

The ornamental design for a humidifying air cleaner, as
shown and described.

DESCRIPTION

FIG. 1 is a front, top and right-side perspective view of a
humidifying air cleaner showing our new design;

FIG. 2 is a front view thereof;

FIG. 3 is a rear view thereof;

FIG. 4 is a top view thereof;

FIG. 5 is a bottom view thereof; and,

FIG. 6 is a right-side view thereof; with the left-side view
being a mirror image thereof.

The broken lines shown represent portions of the humidi-
fying air cleaner and form no part of the claimed design.

1 Claim, 6 Drawing Sheets
